UNITED STATES PATENT OFFICE.

ALBERT L. CULBERTSON, OF MOUNT VERNON, OHIO, ASSIGNOR TO THE CHAPMAN-STEIN FURNACE CO., OF MOUNT VERNON, OHIO, A CORPORATION OF OHIO.

FURNACE AND METHOD OF OPERATING THE SAME.

Application filed January 20, 1926. Serial No. 82,423.

This invention aims to provide a more efficient heat interchange and more uniform heat distribution between the hot gases passing through the heating chamber of a furnace, and material upon the furnace hearth. The invention has particular application to glass furnaces wherein molten glass is heated within a rotary hearth while being brought to and maintained at the proper temperature for subsequent glass making operations, and is illustrated as applied to a furnace of that type. In the drawings—

Fig. 1 is a vertical sectional view of a glass furnace adapted to operate in accordance with the invention, the section being taken on line 1—1 of Fig. 2.

Fig. 2 is a transverse sectional view taken on line 2—2 of Fig. 1, looking in the direction of the arrows.

Fig. 3 is a transverse vertical sectional view on line 3—3 of Fig. 2, looking in the direction of the arrows.

Fig. 4 is a view similar to Fig. 1 with certain parts cut away but illustrating the modified furnace construction.

Fig. 5 is a transverse sectional view showing the invention as applied to a different type of furnace.

In accordance with the present invention, the hot gases upon entering the heating chamber, preferably after being preheated in a recuperator as hereinafter described, are passed laterally across the heating chamber at an upper level from which they heat the

hearth by radiation, and are then passed back across the chamber at a lower level directly over the material carried by the hearth, to heat the latter by direct contact.

The spent gases are then drawn off from the heating chamber at this lower level, preferably to pass downwardly through a recuperator as hereinafter described. In conjunction with the double flow of the hot gases as above described, the hearth is moved

to shift the material to be heated with reference to the path of flow of the gases, thus the movement of the gases and the movement of the material as above described, coacts to produce maximum uniformity of heating.

Heretofore furnaces of the above type have usually been heated by a single inlet and a single outlet port located at the same level, forming uneven currents of the hot gases in different parts of the chamber, and oftentimes exhausting gases before their

heat was sufficiently given up. Also, due to the excessive size of the single port it has been impossible to obtain the intimate mixture of the air and fuel necessary to obtain maximum flame temperatures with their consequent fuel economy.

Moreover, when a series of small ports are used, it is possible to lower the crown of the furnace to its most efficient height for proper combustion and heat radiation. Heretofore the use of a single port for firing and a single exhaust port has necessitated the construction of a high crown which has made it impossible to obtain best efficiency.

According to the present invention, it is possible to project the incoming gases in a comparatively thin and uniform sheet across the upper part of the heating chamber and then pass them back across the hearth in the reverse direction, thus bringing a greater proportion of

the hot gases into direct contact with the material to be heated due to the thinner sheet and better spreading of the gases, and exhausting them at a low level to which only such gases as have given up the greater portion of their heat will tend to fall.

Conversely the hotter gases tend to remain in the upper part of the chamber, thus promoting the maintenance of the two oppositely moving thin sheets or streams of gas above mentioned, and avoiding any tendency of gases to pass out of the chamber before giving up their heat.

In the embodiment of the invention illustrated in Figs. 1 and 3, a hearth 1 is provided to receive molten glass fed in in any suitable manner as by means of spout 2, the hearth being rotated by suitable mechanism, which it is not deemed necessary to describe in detail.

A heating chamber 3 is disposed above the hearth, the inlet ports 4 being located in the upper portion of one side wall of chamber 3; preferably a sufficient number of inlet ports 4 are provided, or ports of such dimensions employed, that the hot gases passing into the chamber 3 therethrough, will form a sheet or stream which extends substantially the full width of the chamber. Oil or gas

burners 5, will be employed in connection with the inlet ports 4.

As indicated by the arrows in Fig. 1, the hot gases first pass substantially horizontally across the chamber 3 at an upper level just beneath the roof 6 of the chamber.

This roof I prefer to make a plane surface, at least in a direction transverse to the flow of the gases, and in furnaces of moderate dimensions the roof preferably is flat, as shown in Fig. 1. The heat of the incoming gases during their travel across the chamber 3, as above mentioned, will be largely given up to the roof 6 and reflected therefrom by radiation down on to the hearth. The invention enables a shallow heating chamber to be employed, thus increasing the effectiveness of the radiated heat, and I have found that the flat roof also increases the effectiveness and uniformity of the radiation as it prevents the focusing of the radiant heat at one spot in the center, which is an inherent disadvantage in the dome type of arch. However, in furnaces of large dimensions, as illustrated by Fig. 4, I prefer to slope the roof 6^a of the heating chamber downwardly toward the hearth 1 at the far side of the heating chamber, thus bringing the sheet of hot gases issuing from ports 4 closer to the hearth of the furnace as such gases pass through the chamber. This produces a more uniform heating of the hearth if the furnace be of large dimensions. As above stated, however, the roof 6^a is preferably plane in a direction transverse to the flow of gases through chamber 3.

After the stream of gases has passed through chamber 3 at an upper level, as above described, the gases are turned downwardly and pass back across hearth 1 at a lower level to the outlet ports 7 which are located in the same side of chamber 3 as ports 4 and at a lower level. During their second travel across the chamber, the gases are directly above hearth 1 and give up their heat to the latter largely through direct contact.

By passing the gases through the heating chamber in the manner above described, a greater proportion of the gases is brought into direct contact with the material to be heated, and the hottest gases are first allocated to the upper part of the heating chamber where they would naturally tend to rise in any event; and after giving up heat, these gases are led to the bottom of the chamber where the cooler gases would naturally tend to fall, and are drawn off at that level after giving up additional heat to the material by direct contact. Thus the natural segregation of the gases in the chamber tends to maintain the upper and lower oppositely moving thin sheets of flame above mentioned. Different areas of hearth, furthermore, will be heated by gases of more uniform temperature, and this, in conjunction with the motion of the hearth itself, will secure uniform heating of the molten glass or other material carried by the hearth.

65 Preferably the incoming air and outgoing

gases are passed through a recuperator denoted generally by numeral 8, such recuperator being of the counter-current type and made up of a series of hollow tile columns 9 (Fig. 1) the tiles of which have vertical 70 passageways 10 to receive the incoming air to be preheated. The spaces between the hollow tile columns are partitioned off by plates 11 to form a series of horizontal passageways 12 at different levels and through 75 which the spent gases pass in zigzag fashion from top to bottom. The recuperator preferably is located at a lower level than chamber 3 whereby the air coming in through passageways 10 to inlet ports 4 will 80 rise as it takes on heat, and the spent gases coming out through ports 7 will pass through the recuperator in a downward direction as they give up their heat.

Fig. 5 illustrates a modified form of the invention wherein the material to be heated will be supported upon a movable hearth 1^a above which is located a heating chamber 3^a. In this embodiment of the invention, inlet ports 4^a are provided in opposite side walls 90 of the heating chamber, and outlet ports 5^a are provided respectively in such side walls at a lower level. Two opposed streams of hot gases are thus formed by the inlet ports 4^a and such streams meet at the center of the 95 heating chamber as illustrated by the arrows in Fig. 5, turn downwardly and pass back over the hearth 1^a in opposite directions to the respective outlet ports 5^a. In this embodiment of the invention the roof 6^b of the heating chamber 3^a preferably is sloped downwardly from each side toward the center of the heating chamber, thus tending to cause the opposed streams of gases to turn 100 downwardly with less disturbance or interference. The downward deflection of the opposed sheets of flame, as above described, prevents overheating at the top of the furnace between the incoming sheets of hot gases, and prevents a zone of unduly low 110 temperature at the bottom of the furnace between the lower sheets of flame.

While certain specific embodiments of the invention have been disclosed, it will be obvious that many changes may be made therein without departing from its principles as defined in the appended claims.

I claim:

1. A furnace having a hearth, a heating chamber disposed above said hearth, means for moving the hearth relative to the chamber, and inlet and outlet ports for heating gases located at different levels on one side of said chamber to cause the gases to pass across the hearth at one level, turn, and then pass back across the hearth at another level before leaving the chamber.

2. A furnace having a hearth, a heating chamber disposed above said hearth, means for moving the hearth relative to the chamber,

- ber, one or more inlet ports located at one side of said chamber, adapted to cause heating gases to pass across the hearth, and one or more outlet ports for said gases located 5 at the same side of said chamber and beneath said inlet ports, whereby the gases will turn downwardly and pass back across the hearth at a lower level to said outlet ports.
3. A furnace having a hearth, a heating chamber disposed above said hearth, means 10 for moving the hearth relative to the chamber, said chamber including a roof adapted to reflect heat downwardly on to the hearth by radiation, one or more inlet ports for 15 heating gases located at one side of the chamber adapted to cause the gases to pass across the roof and supply heat to the hearth by radiation, one or more outlet ports located in the same side of said chamber beneath said 20 inlet ports, whereby said gases after passing across the chamber adjacent the roof as above mentioned, will turn downwardly and pass back across and in contact with the hearth to said outlet ports.
- 25 4. A furnace having a hearth, a heating chamber disposed above said hearth, means for moving the hearth relative to the chamber, a recuperator disposed below the level of said chamber having passageways leading 30 upwardly for gases to be heated and other passageways leading downwardly for the spent gases, together with one or more inlet ports communicating with said first mentioned passageways and disposed at one side 35 of said chamber to project hot gases laterally thereacross, and one or more outlet ports communicating with said second mentioned recuperator passageways, said outlet ports being disposed on the same side of and beneath 40 said inlet ports, whereby incoming gases rise through the recuperator, pass horizontally across the upper portion of said chamber, turn, and pass back across the chamber at a lower level and through said 45 outlet ports to the spent gas passageways of the recuperator.
5. The method of operating a furnace having a hearth and a heating chamber disposed above the hearth which comprises passing a 50 sheet of hot gases substantially horizontally across said chamber, passing the gases back across the hearth at a different level in the reverse direction and simultaneously moving the material carried by said hearth in a plane substantially parallel to the flow of the 55 hot gases over the hearth.
6. A furnace having a heating chamber,
- inlet ports for heating gases located at opposite sides of said chamber at an upper level, and outlet ports located respectively 60 at a lower level than the inlet ports, whereby opposed sheets of hot gases are formed in said chamber at an upper level, means located at the meeting point of said sheets to deflect them downwardly, whereby each respective sheet turns back on itself and passes back across the hearth at a lower level to its respective outlet ports.
7. A furnace having a heating chamber, 70 inlet ports for heating gases located at opposite sides of said chamber at an upper level, and outlet ports located respectively beneath said inlet ports whereby opposed streams of hot gases are formed in said chamber at an upper level, which streams turn downwardly and back to pass out of their respective outlet ports at a lower level, the roof of said heating chamber being depressed in the central portion of the chamber.
8. A furnace having a heating chamber, 75 means for admitting hot gases respectively near the tops of opposite walls of said chamber, means between said points of admission for deflecting said gases downwardly, and means for withdrawing said gases at points 80 respectively beneath the points of admission above mentioned.
9. The method of heating material which 85 consists in moving the material and simultaneously causing hot gases to flow twice over the moving material at different levels.
10. A furnace having a hearth, a heating chamber disposed above said hearth and including a roof adapted to reflect heat downwardly on to the hearth by radiation one or more inlet ports for heating gases located 90 at one side of the chamber adapted to cause the gases to pass across the roof and supply heat to the hearth by radiation, one or more outlet ports located in the same side of said chamber beneath said inlet ports, whereby 95 said gases after passing across the chamber adjacent the roof as above mentioned, will turn downwardly and pass back across and in contact with the hearth to said outlet ports, the under surface of said roof being 100 substantially plane at least in the direction transverse to the flow of the hot gases thereacross.

In testimony that I claim the foregoing, I have hereunto set my hand this 4th day of January, 1926.

ALBERT L. CULBERTSON.
